BOTTLE CLEANER CONFORMABLE TO
SHAPE OF BOTTLEYuriko Nishizaka, Brooklyn, N. Y., and Jenshiro
Teruya, Hartford, Conn.

Application June 15, 1946, Serial No. 677,068

1 Claim. (Cl. 15—212)

1

This invention relates to collapsible and expandable brushes for use in cleaning large vessels having small necks through which the brush may be inserted.

The principal object of this invention is the provision of a device of the character described which is readily collapsible and equally readily expandable and adapted to conform to the contours of the vessel or other article in which it is used.

Another object of this invention is the provision of a device of the character described, which has reversible brushes and whose brushes may very readily be replaced when they are worn or otherwise unsuited for use.

Still another object of this invention is the provision of a device of the character described which has few parts, all of which are readily accessible for washing and cleaning purposes so that the device may be kept clean and sanitary at all times.

A preferred embodiment of this invention is shown in the accompanying drawing in which—

Fig. 1 is a side elevational view thereof showing it in operative position in a bottle having a relatively wide base and a relatively narrow neck;

Fig. 2 is an enlarged side elevational view of said device showing it in contracted position partly in section to reveal the spring construction of the brushes;

Fig. 3 is a transverse section on the line 3—3 of Fig. 2; and

Fig. 4 is a fragmentary enlarged section through the lower part of the device showing how the spring construction is connected to the handle of the device.

Referring now particularly to Fig. 2, it will be seen that the device herein claimed includes a hollow handle 10 and a second handle 11 slidably mounted within the handle 10. Handle 11 is provided with an eye portion 12 at its upper end for ease in holding, and at its lower end it is provided with a pin 13 set transversely therein for a purpose which will shortly appear. The hollow handle 10 comprises a tubular member which is split or slotted longitudinally for the member part of its length beginning at its bottom end. The slot 14 thereby formed is adapted to accommodate the pin 13 on the handle 11. The bottom end of the hollow handle 10 is provided with external screw threads 15, and an internally threaded cap 16 is mounted thereon. It will be noted from Fig. 4 that cap 16 is provided with a slot 17 which transforms said cap into a bifurcated member. The slot is adapted to receive a

2

wire 18 as shown in Fig. 4, so that when the cap is tightly screwed to the hollow handle 10, a tight grip upon the wire 18 is effected.

Slidably mounted on the outside of hollow handle 10 is a slide 20. This slide is provided with a transverse hole adapted to receive the ends of the pin 13. When the pin is inserted into said hole, it will be understood that said slide 20 will be movable integrally with the inner handle 10. When the handle 11 is moved longitudinally with respect to the hollow handle 10, a corresponding movement of the slide 20 will result. Such longitudinal movement will be limited at one end by the cap 16 and at the other end by the end of the slot 14.

It will be seen in Fig. 2 that the slide 20 is provided with two oppositely disposed downwardly extending ears 22. And it will be seen from Fig. 3 that these downwardly extending ears are each bifurcated.

A spiral or coil spring 25 which is separated into two portions of equal size, said portions being connected by the wire 18 previously described, is provided at its two ends with eye portions 26. It will be noted in Fig. 4 that the wire 18 is integral with the spring 25 and that it really forms a part thereof. Pins 27 affixed to the bifurcated ears 22 of slide 20, connect the spring 25 to said slide by means of the eyes 26 which are mounted on said pins. A cleaning element 30 is mounted on the spring 25, and more particularly a pair of such elements is mounted on the two portions of the spring 25 above described. This cleaning element is of a flexible type and it may be made of a fuzzy tubular fabric such as shown in Fig. 4, or it may be made of ordinary bristles used in cleaning brushes.

To operate the device above described, the handle 11 is pulled out of the hollow handle 10 to the outwardly extending position shown in Fig. 2. The slide 20 is thereby brought upwardly along hollow handle 10 and in consequence, the two cleaning elements are brought into the position shown in Fig. 2. The device is now inserted 45 through the narrow neck 30' of bottle 31 and when the washing elements are positioned within the broad base of said bottle, the handle 11 is pushed downwardly into hollow handle 10 to the position shown in Fig. 1. This causes downward movement of the slide 20 and the spring 25 is caused to expand until it assumes the form of the inner walls of the bottle 31. Since the cleaning elements are mounted on said spring, they too will assume this form which is shown in Fig. 1. 50 It is now possible to use the device in the usual

manner and thereby to clean the inside walls of the bottle.

It will be understood from the foregoing that only a preferred embodiment of this invention has been described, and that modifications may be incorporated therein without departing from the basic principles of the invention. For example, instead of the eye 12 at the top of handle 11, a knob or other similar device may be substituted. As has already been indicated any conventional kind of cleaning element may be used on the spiral spring 25. It may be mounted on the outside of the spring or it may be interwoven with the spring.

We claim:

A cleaning device of the character described comprising a slotted tubular handle, an inner handle slidably mounted therein, and a cleaning element connected intermediate its ends to the bottom of the slotted hollow handle and connected at its ends through the slot of said slotted

5 handle to the bottom of the inner handle, said cleaning element comprising a flexible resilient member which is adapted to conform to the contours of the vessel in which it is operated when the inner handle is moved downwardly toward the bottom of the hollow handle.
